UNITED STATES PATENT OFFICE.

DAVID H. HOUSTON, OF HUNTER, NORTH DAKOTA.

DAYLIGHT-LOADING PHOTOGRAPHIC-ROLL HOLDER.

SPECIFICATION forming part of Letters Patent No. 694,921, dated March 4, 1902.

Original application filed March 12, 1897, Serial No. 627,094. Divided and this application filed January 28, 1898. Serial No. 668,244. (No modcl.)

To all whom it may concern:

Be it known that I, DAVID H. HOUSTON, a citizen of the United States, residing at Hunter, in the county of Cass and State of North Dakota, have invented certain new and useful Improvements in Daylight-Loading Photographic-Roll Holders; and I do hereby declare the following to be a full, clear, and exact description of the invention, such as will enable others skilled in the art to which it appertains to make and use the same.

This application is a division of the application filed by me on March 12, 1897, Serial No. 627,094, for photographic-roll holders.

My invention relates to an improved photographic-roll holder in which are used cartridges of sensitized film.

The object of my invention is the provision of a separable spool-holding roll-holder for use in cameras, said roll-holder having a front slide to exclude light from the sensitized film when the roll-holder is separated from the camera, so that plate-holders can be used interchangeably with the roll-holder. My roll-holder has one compartment for holding the spools of sensitized film and a sight-aperture positioned in and through the film-support board in any suitable position; but I prefer to place a walled sight-passage through the top of the roll-holder casing, said sight-passage leading to a sight-aperture in the film-support board and being so arranged that a good light can be obtained in the passage-way leading to the sight-aperture through the film-support board, so as to allow of indicia being observed and indicate the position of the sensitized film in the roll-holder.

My invention consists of a daylight-loading photographic-roll holder of improved construction suitable for using spools of cartridge-film and having a sight-aperture through the film-support board of the roll-holder; and it has combination of parts which are hereinafter described, and the novel features pointed out in the claims of the specification.

In the drawings which form part of this specification similar characters of reference denote similar parts.

Figure 1 represents a perspective view of my roll-holder, taken from the rear. Fig. 2

represents a central vertical transverse sectional view of the roll-holder. Fig. 3 represents a horizontal sectional view taken on the line X X of Fig. 2 and showing a section 55 through the walled sight-passage leading to the sight-aperture of the roll-holder. Fig. 4 represents a vertical sectional view taken lengthwise of the casing on the line Y Y of Fig. 3 and showing a section through the 60 walled sight-passage leading to the sight-aperture of the roll-holder. Fig. 5 represents a vertical sectional view taken lengthwise of the casing and showing a modified construction having a sight-passage in the bottom of 65 the roll-holder casing.

In the drawings, A designates the casing, which has in its top a sight passage-way B, which passage-way may have walls C and a bottom C'. In the interior of the casing near 70 the front thereof is the film-support D, through which film-support there is a sight-aperture covered with a transparent plate E, made of material such as celluloid slightly colored and adapted to exclude actinic rays of light and 75 prevent the light from detrimentally effecting the sensitized film by passing through the sight-aperture.

In the roll-holder are the film-spool F and the reel-spool F', which carry the sensitized 80 film, and said spools are centered on the spool-centering devices P. The rounded guides G are positioned near to the opposite interior front corners of the one-compartment roll-holding casing, and the sensitized film should 85 be passed around the said rounded guides and in front of the film-support D.

Sliding in the slot H at the front side of the roll-holder casing is the slide J, which when withdrawn allows the sensitized film to be exposed to the rays of light coming from the view through the lens after the roll-holder has been placed in the camera and the shutter of the lens operated.

In the rear side of the roll-holder casing 95 there is a door K, which door is adapted to be opened to and allow of access to the interior of the casing.

From this description, taken in connection with the drawings, the construction of my roll-holder invention can be readily understood.

In operating the roll-holder it is applied to

a camera in the same manner as a plate-holder, and the roll-holder is prepared for use by opening the casing of the roll-holder and placing a spool of sensitized film in position on the spool-centering devices, then by passing the sensitized film around in front of the rounded guides and in front of the film-support board and sight-aperture of the roll-holder, and by connecting the wrapper of the sensitized film to the reel-spool. The front slide and the rear door are then closed, and the sensitized film may be wound forward until the first number, letter, or indicia appears opposite to the sight-aperture, denoting that the sensitized film is in position for the first exposure upon a view. The winding forward of the film is done upon the reel-spool by turning it with a winding-key in the direction shown by the arrow-mark, and if by accident the film is wound a little too far it can be readjusted back by simply placing a winding-key upon the shaft of the supply-spool-centering device and winding backward, meanwhile observing at the sight-aperture for the indicia that indicate the movement of the sensitized film.

From the foregoing description it can be understood that I provide a photographic-roll holder of improved construction, and that my improved roll-holder is adapted to be used interchangeably with plate-holders in the same camera, and that my invention is a decidedly practical roll-holder having a film-support board, and a sight-aperture leading therethrough, and a true division of my former application.

I claim—

1. In a photographic-roll holder the combination of a casing having a sight-opening in its top, a film-support board in the roll-holder casing, the said film-support board having a sight-aperture therethrough, said casing and said film-support board connected by walls forming a sight-passage through the top of the casing and through the film-support board, whereby visual observation can be had from the outside of the roll-holder casing through the film-support board.

2. In a photographic-roll holder the combination of a casing having a front opening, a

slide in said front opening, a film-support board having a sight-aperture therethrough, rounded guides for the sensitized film positioned at opposite ends of the film-support board, spool and reel centering devices in the 55 casing, the roll-holder casing having a sight-passage leading from the top of the casing to a sight-aperture in the film-support board, said sight-passage in the casing adapted to allow of the observation of indicia, and a 60 door in the rear of the casing.

3. In a photographic-roll holder the combination of a casing having a front opening, a slide in said front opening, rounded guides for the sensitized film positioned at opposite 65 interior ends of the casing, a film-support board having a sight-aperture therethrough, said film-support board positioned in line between the rounded guides, one chamber only for holding the supply and reel spools, spool 70 and reel centering devices in the said chamber, the roll-holder casing having a sight-passage leading from the outside of the casing through to the said sight-aperture in the said film-support board, said sight-passage adapted to 75 allow of the observation of indicia, and a door in the rear of the casing.

4. In a photographic-roll holder the combination of a casing having a front opening, a slide in said front opening, rounded guides 80 for the sensitized film, said rounded guides positioned near to the front interior corners of the roll-holder casing, a film-support board positioned in line between the said rounded guides, said film-support board having a sight-aperture therethrough, one chamber for holding the spools of sensitized film, supply-spool 85 and reel-spool centering devices in the said chamber, the roll-holder casing having an incased sight-passage leading from the outside of 90 the casing through a suitable part thereof and leading to a sight-aperture through the film-support board of the roll-holder, whereby indicia can be observed through the said incased sight-passage, and a door in the rear of 95 the casing.

DAVID H. HOUSTON.
